UNITED STATES PATENT OFFICE.

HENRY C. MILLIGAN, OF SOUTH ORANGE, NEW JERSEY, ASSIGNOR OF
ONE-HALF TO JOHN S. BROOKS, OF BROOKLYN, NEW YORK.

STOVE-BOARD.

SPECIFICATION forming part of Letters Patent No. 247,389, dated September 20, 1881.

Application filed August 25, 1881. (No model.)

To all whom it may concern:

Be it known that I, HENRY C. MILLIGAN, a citizen of the United States, residing at South Orange, New Jersey, have invented new and useful Improvements in Stove-Boards, of which the following is a specification.

Prior to my invention the disadvantages of heating and other stoves resting directly upon the floor was felt, and a means was sought for protecting the same from the radiated heat and falling coal and ashes. This resulted in the production of what has become well known in the trade as "sheet-metal stove-boards." Various improvements have from time to time been suggested, involving peculiarities of construction, and having in view the strengthening and beautifying of such boards; and with special reference to the beautification of the same it has been suggested to ornament them by embossing a design thereon—that is, raising a given design around the board near its circumference, or at any other desirable locality. In this class of boards so ornamented it has been found that while the ornamentation serves to beautify the board it also forms receptacles between the embossed surfaces or salient points for the reception of coal, ashes, dirt, &c., and that the removal of the same is quite troublesome and difficult. The object of my invention is to overcome in a great measure this last-named disadvantage, and at the same time to produce a highly-ornamented board, the character of the ornamentation to be such that while it will avoid the accumulation of dirt in a great measure, it is also protected from undue wear and oblitera-
tion; and with these ends in view my invention consists of a sheet-metal stove-board having near its circumference, or at any desired location, a pleasing design impressed or indented in the surface of the metal, such impressed or indented design being partially filled with a contrasting cement or paint to bring out in relief the metal between such design, and give to such portions of the metal the appearance of embossed surfaces, such apparently-embossed surfaces serving as a protection against the defacement or abrasion of the cement or paint, as will be hereinafter more fully explained.

In order that those skilled in the art to which my invention appertains may fully understand the same, I will proceed to describe the peculiarities of construction, referring by letters to the accompanying drawings, in which—

Figure 1 is a plan view of a portion of a stove-board embodying my invention, and Fig. 2 a section taken at the line *x x* of Fig. 1.

Similar letters indicate like parts in both figures.

A represents an ordinary sheet-metal stove-board, stiffened and strengthened by continuous embossed beads B B, concentric with the center point of the board, the outer edge of the board being formed with a stiffening-bead, as shown, and in addition thereto it may be strengthened by radially corrugating the same and bending it under, as fully described in Letters Patent to John S. Brooks, dated January 23, 1877.

C represents a design, of any desired character, impressed in the top surface of the board by revolving rollers or dies, leaving the metal D between and surrounding said design in about its original plane.

E is a coating of cement or paint, of any suitable and contrasting color, placed upon the impressed or indented design. This cement or paint E, when dry, is designed to have its upper exposed surface slightly below the plane of the surrounding bright metal, so that while it affords little if any opportunity for the accumulation of dust and dirt, it is safely guarded by the surrounding metal from abrasion or defacement.

It will be observed that the relation of the salient parts of the metal and the guarded and contrasting paint or cement is such that the contrast is always preserved, and is enhanced by any and all wear or cleansing of the salient parts of the metal.

There are many ways which may be adopted for producing my improved stove-boards, the most desirable method so far suggested, but which I do not claim as of my invention, being to roll in the design between revolving dies or rollers, then to paint over or cover the indented and salient designs formed by such rolling-in process with paint or semi-fluid cement, and subsequently, when said colored

paint or cement has partially or sufficiently dried or hardened, to turn the stove-board upon a flat surface and upon a pivot passing through its center, and to skim or scrape off the paint or cement from the salient parts of the metal by a chisel or other suitable instrument, leaving the intaglio portions perfectly covered.

It will be observed that the points of juncture between the impressed or indented and salient portions of the metal are not abrupt angles, but are, by the nature of the rolling-in process and the character of the metal, (such as is ordinarily used for the purpose,) slightly arched or curved, so that the colored paint or cement creeps up and clings to said surfaces, and even after the salient parts of the metal shall have become slightly worn there will still remain an intaglio design.

I do not wish to secure by Letters Patent

an improvement in the art of ornamenting metal; but

What I do claim is—

As a new article of manufacture, a sheet-metal stove-board having ornamental figures impressed or indented therein, such ornamental figures being covered in the manner described with a paint or cement, to produce contrast and prevent accumulation of dirt, while said paint or cement is protected from wear, substantially as hereinbefore set forth.

In testimony whereof I have hereunto set my hand in the presence of two subscribing witnesses.

HENRY C. MILLIGAN.
